UNITED STATES PATENT OFFICE.

ANDREW J. MILLS, OF WEIR, MISSISSIPPI.

PAPER EXTRACT-HOLDING CUP.

1,157,568.

Specification of Letters Patent. Patented Oct. 19, 1915.

Application filed December 17, 1912. Serial No. 737,344.

To all whom it may concern:

Be it known that I, ANDREW J. MILLS, a citizen of the United States, residing at Weir, in the county of Choctaw and State 5 of Mississippi, have invented certain new and useful Improvements in Paper Extract-Holding Cups, of which the following is a specification.

This invention comprehends certain new 10 and useful improvements in sanitary drinking cups and relates more particularly to paper cups of this nature especially adapted for holding flavoring extracts.

The primary object of the invention re- 15 sides in the provision of a drinking cup which may be formed from a single piece of paper, which is sealed so as to retain there- in a flavoring extract, and which is pro- vided with suitable perforations whereby a 20 portion of the paper may be removed to open the cup.

The invention also aims to generally im- 25 prove cups of this nature to render them more useful and commercially desirable.

With these and other objects in view as 30 will become more apparent as the descrip- tion proceeds, the invention consists in cer- tain novel features of construction, combi- nation, and arrangement of parts, as will be hereinafter more fully described and claimed.

For a complete understanding of my in- 35 vention, reference is to be had to the fol- lowing description and accompanying draw- ings, in which,

Figure 1 is a side elevation of my im- 40 proved cup, Fig. 2 is a perspective view of the same, showing the cup open and ready for use, Figs. 3 and 4 are longitudinal and transverse sectional views, respectively, and, Fig. 5 is a side elevation, showing a portion 45 of the cup partly removed to illustrate the manner of opening the same.

Referring in detail to the drawings by 50 numerals, 1 designates, generally, a drinking cup formed from a single sheet of paper and having the side walls 2 and 3. The side wall 3 carries a flap 4, which is folded over and sealed to the wall 2, said side wall 3 also carries a bottom flap 5, which is sealed to the wall 2 and flap 4, thus closing the bottom of the cup. The top edges of

the cup are also sealed together and the side walls 2 and 3 are provided adjacent said top edges, with the perforations 6. To open 55 the cup in order that it may be filled, the portions 7 and 8 of the side walls 2 and 3, respectively, are removed, this being easily accomplished because of the perforations 6.

Having formed the drinking cup as be- 60 fore stated, and before closing the same en- tirely, I place therein a suitable flavoring extract, preferably in a powdered form, such as will not readily leak out through the seams of the cup or the perforations 6. 65 After the extract has been placed within the cup, the same is completely sealed and is then ready for marketing. It is to be under- 70 stood that extracts of any flavor may be placed within the cups and since they are easily soluble in water, will produce a pleasant drink without trouble or expense.

It will be seen that my improved extract- 75 holding cup may be cheaply manufactured and will prove to be readily salable.

As the side walls 2 and 3 are sealed to- 80 gether at a point adjacent the rows of per- forations 6, the inner faces of the side walls adjacent the rows of perforations are held in intimate contact, preventing the contents 85 of the cup from escaping through the per- forations and preventing dust and other for- eign matter entering the cup through the perforations.

It is to be understood that while I have 85 shown and described the preferred embodiment of my invention, I do not wish to be limited to this exact construction, combi- nation, and arrangement of parts, but may make such changes as will fall within the 90 spirit and scope of the invention.

Having thus described my invention, what I claim is:—

A cup of the character set forth comprising side walls having alined rows of perforations near their upper ends and having their side and bottom edges connected to- 95 gether, the upper portions of the side walls being sealed together at a point adjacent the rows of perforations to close the upper end 100 of the cup and to hold the inner faces of the side walls adjacent the rows of perforations in intimate contact so as to prevent the contents of the cup escaping through the per-

forations and so as to prevent dust and other foreign matter entering the cup through the perforations, the perforations permitting the connected upper portions of 5 the side walls to be removed when it is desired to use the cup.

In testimony whereof I affix my signature in presence of two witnesses.

ANDY J. MILLS.
